By atty., Inventor,

Levi B. Stuart

UNITED STATES PATENT OFFICE.

LEVI B. STUART, OF SEYMOUR, CONNECTICUT, ASSIGNOR OF ONE-HALF TO
W. E. ROBERTS, OF SAME PLACE.

TRUSS.

SPECIFICATION forming part of Letters Patent No. 381,089, dated April 10, 1888.

Application filed December 20, 1887. Serial No. 258,482. (No model.)

To all whom it may concern:

Be it known that I, LEVI B. STUART, of Seymour, in the county of New Haven and State of Connecticut, have invented a new Improvement 5 in Trusses; and I do hereby declare the following, when taken in connection with accompanying drawings and the letters of reference marked thereon, to be a full, clear, and exact description of the same, and which said 10 drawings constitute part of this specification, and represent, in—

Figure 1, an outside or front view of the pad and so much of the frame as is necessary to illustrate the invention; Fig. 2, a side view of 15 the pad, looking toward the forward end of the frame; Fig. 3, a vertical section through the frame and partial section of the pad, illustrating the connection of the spring with the frame and pad; Fig. 4, a top view of the pad 20 and frame; Fig. 5, the spring detached.

This invention relates to an improvement in trusses, having special reference to the attachment of the pad to the frame, the object of the invention being to give to the pad a self-adjustable bearing or lifting action; and it consists 25 in a pad hung to the frame as upon a hinge, with a spring-pressure between the frame and pad below the hinge, the tendency of which spring is to turn the body upon the 30 hinge and give to the body an upward lifting action or pressure.

In illustrating the invention I show the frame substantially such as illustrated in Patent No. 237,926, granted for my invention 35 February 15, 1881, but only show the front portion of the frame to which the body is attached, that being sufficient for the illustration of the invention.

A A represent the two wires which form the 40 frame, but which are connected by a bend, B, at the extreme forward end of the frame.

C represents the pad, which will be of a shape according to circumstances and as in other constructions of truss. The pad is 45 hinged to the frame. The point of hinging between the frame and pad being below the upper edge of the pad, the hinging is made by means of a helical spring. This spring is formed in two parts, D D, surrounding the 50 upper bar of the frame, and so that the bar it-

self forms a pintle or support for the spring. The spring is made from a single piece of wire, the portion of the wire between the two parts D D of the spring being bent into U shape, as seen in Fig. 5, E representing the 55 U-shaped portion of the spring. This U-shaped portion extends down onto the pad, as represented in Figs. 2 and 3, and so as to take a firm bearing thereon. The extreme ends of the spring are made fast to the frame, as here 60 represented. This is done by extending the legs to the lower part of the frame and bending the ends around that part of the frame, as represented at a a, Fig. 1. The relation of the part E of the spring to the fixed legs a is such 65 as to give the pad an inclination to the frame—that is, so that the pad stands away from the lower part of the frame, but is yieldingly held by the spring, so that pressure upon the body may force the pad toward the frame, as indicated in broken lines, Fig. 2.

The spring is best secured to the frame by a plate, F, one end of which is bent around the upper part of the frame, as at G, and, extending downward, incloses the part E of the 75 spring, and is secured to the pad by a screw, H, which forms a pivot on which the pad may be permitted a limited amount of oscillation to give it the required transverse position. A yoke, I, is attached by its upper end to the 80 pad above the frame, as at b, the yoke extending outside the frame, thence down to the body below the pivots, where the lower end of the yoke is adjustably secured to the pad, as at d, this adjustability being produced by 85 means of a screw, e, which may be screwed into or withdrawn from the pad, so as to give a greater or less amount of play for the pad. The yoke comes to a bearing upon the frame under the action of the spring, as represented 90 in Fig. 3, which limits the extent of rise, swing, or upward lift which may be imparted to the pad, and this extent of movement may be adjusted by means of the screw e. Normally, however, the adjustment of the yoke 95 should be such that the pad will rest on the person without substantial contact of the yoke, and so that the pressure will always be yielding.

The action of the spring upon the pad is to 100

give it an upward lift or pressure—an effect which is desirable in this class of trusses; but at the same time it permits the pad to yield under the movements of the body, so that it 5 will always retain the same relative position to the parts to which it is applied.

It will be evident that while the yoke is desirable, in order to limit the extreme upward lift of the pad, it is not essential to the invention and may be omitted.

I claim—

1. A frame composed of two parts, A A, united at the forward end, the pad C, hinged to the upper part A of the frame, the pad 15 extending downward therefrom, with a helical spring surrounding the upper part of the frame as a pintle, the end of the spring made fast to the said frame, the spring constructed with an extension or arm downward from the

coils onto the pad below the frame, substantially as described, the said spring operating to turn the body upward from the lower part of the frame and give to it a lifting action.

2. The combination of a frame composed of two parts, A A, a pad hinged to the upper 25 part of the frame, a spring between the frame and pad to operate upon the body of said pad below the hinge, and a yoke, I, outside the frame, the yoke secured at its upper end to the pad both above and below the frame, the 30 said yoke serving to limit the extent of the lifting action of the pad, substantially as described.

LEVI B. STUART.
